UNITED STATES PATENT OFFICE.

GEORGE H. HENKEL AND JOHN KUNZ, JR., OF MIDDLETOWN, OHIO,
ASSIGNORS OF ONE-SIXTH TO WILLIAM LING AND HENRY VAN
SICKLE, OF SAME PLACE.

PAPER-SACK HOLDER AND PRINTER.

SPECIFICATION forming part of Letters Patent No. 639,678, dated December 19, 1899.
Application filed February 27, 1899. Serial No. 706,958. (No model.)

To all whom it may concern:

Be it known that we, GEORGE H. HENKEL and JOHN KUNZ, Jr., citizens of the United States, residing at Middletown, in the county 5 of Butler and State of Ohio, have invented certain new and useful Improvements in Paper-Sack Holders and Printers; and we do hereby declare that the following is a full, clear, and exact description of the invention, which 10 will enable others skilled in the art to which it appertains to make and use the same, reference being had to the accompanying drawings, and to the letters of reference marked thereon, which form a part of this specification. 15

Our invention relates to improvements in paper-sack holders and printers for retail stores—such, for example, as grocery stores, &c.

20 The object of the invention is to provide a sack holder and printer in which the sacks are neatly printed as they are removed from said holder.

The following detailed description, taken in 25 connection with the accompanying drawings, will clearly define the structural features and advantages of our invention.

Figure 1 is a front elevation of the mechanism and supporting-frame. Fig. 2 is a side 30 elevation of the same, part of the framework being broken away to disclose the sack-compartments. Fig. 3 is a longitudinal elevation of the type-cylinder. Fig. 4 is a cross-sectional view of the same.

35 Throughout the specification similar reference characters indicate corresponding parts.

The casing or cabinet inclosing the supporting-frame A may be of any ornamental design. Within the frame A there are three or more 40 upright walls B, which provide compartments C C C for different sizes of paper sacks D. The sacks rest upon inclines E in order to present their upper ends one above the other in convenient positions to be taken hold of by 45 the fingers. On the upper end of each wall B there is a roller F, that extends across and facilitates the removal of the sacks. An ink-roller 1 has its journals 2 mounted in slots 3, which permit of suitable movement being im- 50 parted to the said roller to apply ink to the

type-cylinder 13 at stated times. The front of the frame in which the ink-roller and type-cylinder are mounted is closed by a door G, hinged at g.

4 designates a short lever pivoted on each 55 side of the frame at 5. There are openings through the front ends of said levers through which pins 6 project. The said pins have heads 6^a, that lie below the journals 2 of the ink-roller. 7 is an adjusting-nut on the lower 60 ends of said pins, and 8 is a tension-spring on the upper portion of each pin. By means of these devices the inking-roller has a suitable bearing. On the rear ends of the levers 4 there are trip-pawls 9, which are maintained 65 in the positions shown by springs 10. The ink-trough 11 is mounted below said ink-roller, and the ink is applied to said roller by means of any suitable absorbent material 14, which is suitably suspended or supported in the ink-trough. Any other suitable means for applying the ink from the trough to the roller 70 may be employed. The ink-roller is elevated against the type-cylinder 13 and lowered by segmental cams 12 engaging and releasing the 75 trip-pawls 9. The type-cylinder has its journals 15 mounted in slots 16 in the sides of the frame and are secured in said slots by pins 17. The said cylinder, further, has a longitudinal 80 groove 18 in its surface, in which is secured 85 the rubber or other material 19, having the type, by means of a clamp or bar 20, which fits in said groove and is secured to the cylinder by screws or otherwise. On the shaft of the type-cylinder and at each end there is a loose 85 wheel or roller 21, which facilitates the removal of the paper sacks as they are drawn out between the type-cylinder and pressure-roller 22. The latter roller is covered with felt or other soft material. Adjacent to the type-cylinder there is mounted a roller 23, over 90 which the sacks are drawn, and thereby prevented from coming in contact with the type-cylinder only at the point where the impression is made. The front one of the rollers F 95 also serves to prevent the sacks from coming in contact with the inking-roller when being removed.

25 designates a guard or cover inclosing the pressure-roller 22.

On each end of the shaft of the type-cylinder there is a spur-wheel 26, that engages the segment-gears 27. These gears and the segment-cams 12 move on a common axis 28, as do also the arms 29, which carry the pressure-roller 22. These arms 29 and the cam-segments 12 are integral parts preferably. 30 is a notch in the upper portion of said cams, and 31 and 32 are arms or extensions from the rear part of said cams. The latter arm, to wit, 32—affords means for attaching springs 33, said springs being also attached to the frame. Arm 31 has a stop 31^a.

34 designates stops on the frame for the segmental cams 12 at the point from which said cams are moved downward. 35 are stops on the frame for the segment-gears 27 at the point from which the said cams are moved downward. On each of the arms 29 there is 29 a trip-pawl 36, held in position by a stop 37 on said arms. In the path of these pawls there is an inclined projection 38 on each side of the frame.

The mode of operation is as follows: Each compartment C may contain a number of sacks, say fifty. The drawings show one compartment with sacks therein. The sacks are caught hold of singly by the hand and are pulled out a suitable distance to a point 30 where the printing is to begin. The pressure-roller 22 is then caught hold of and lowered by the other hand grasping the cover 25. This immediately elevates the inking-roller 1 in contact with the type-cylinder by 35 cams 12 coming in contact with the trip-pawls 9. The segment-gears 27 are moved by pawls 36 engaging with the inclined projections 39 on the inner sides of said gears. One complete downward movement of said 40 segment-gears causes a movement of the type-cylinder sufficient to present all of the type to the ink-roller. In the meantime the notches 30 in the cam-segments arrive at the pawls 9 and the ink-roller is allowed to move down 45 from contact with the type-cylinder. The segment-gears are limited in the downward movement by stops 40 thereon coming in contact with stops 41 on the frame. At this period the pawls 36 release the segment-gears by 50 coming in contact with the inclines 38. The sack is then pulled out, the pressure-roller being held down against it in the meantime. This movement of the sack rotates the type-cylinder back, and the segment-gears are 55 driven back by the wheels 26. The said segment-gears are moved in this manner to, say, the point x, Fig. 2, when the stops 44 thereon engage with stops 31^a on the arms 31 of the cams. The pressure-roller is then re- 60 leased, and the cams are moved up to their normal positions by springs 33. Lugs or projections 45 on said cams then engage with similar projections 45^a on the inner sides of the segment-gears, and the cams and gears 65 are moved back together to their normal positions, as shown in Fig. 2. When stops 44 engage with stops 31^a on the back movement,

the type-cylinder will be idle and the pressure-roller will arrive in a position over the groove 18 in the type-cylinder and rest on the wheels 21. This allows the paper sacks to be drawn over said wheels out of contact with the ink on the type-cylinder. When all of the compartments are filled with different sizes of sacks, those in the front compartment are of the shorter size in order that the sacks in the rear compartments may be drawn over the tops of them in position to be printed. When only one size of sack is used, as is shown in Fig. 2, it is immaterial what size of sacks are placed in the front compartment. For example, sacks of the length shown in the front compartment, Fig. 2, would properly belong in one of the rear compartments and shorter sacks placed in the front compartment, if all the compartments were used. While the means herein shown and described successfully accomplish this, yet some variations might be made in the details of construction without departing from the main features of the invention.

Having described our invention, we claim—

1. In a paper-sack holder and printer, the combination with a type-cylinder, and means for inking said cylinder, of gears and cams movable simultaneously to elevate the inking devices and rotate the type-cylinder, and a pressure-roller, movable with said cams and gears and adapted to hold the sacks against the type-cylinder, substantially as specified.

2. In a paper-sack holder and printer, the combination with a type-cylinder, and an inking-roller, of cams and gears for simultaneously elevating the inking-roller and rotating the type-cylinder, means on said cams for engaging with the gears in their back and forward movements, and a pressure-roller to hold the sacks against the type-cylinder, substantially as specified.

3. In a paper-sack holder and printer, the combination with a type-cylinder, and inking-roller therefor, of cams for elevating said inking-roller, gears for rotating said type-cylinder, pawls carried on the cams for engaging said gears and causing them to rotate with the cams, and means for disengaging said pawls from the gears upon the completion of each downward movement, substantially as specified.

4. In a paper-sack holder and printer, the combination with a type-cylinder, and inking-roller, of cams for elevating said inking-roller against the type-cylinder, segmental gears for rotating said type-cylinder, means carried on said cams and gears for causing said gears to move downwardly simultaneously with the cams, and means for disengaging said cams and gears upon the completion of their downward movement.

5. In a paper-sack holder and printer, the combination with a type-cylinder, and an inking-roller, of segmental cams for elevating said inking-roller, spur-wheels at the ends of said type-cylinder, segmental gears engaging

with said spur-wheels, and means on the cams for engaging said segmental gears after said cams have started to move, and a pressure-roller carried on said cams, substantially as specified.

6. In a paper-sack holder and printer, the combination with a frame adapted to hold paper sacks in upright position, a type-cylinder, and an inking-roller for applying ink to said cylinder, of segmental gears, and cams adapted to rotate the type-cylinder and elevate the inking-roller, means on the cams for effecting the entire movement of said segmental gears in one direction, and means for partially moving them in their return movement, and a pressure-roller carried by said cams for holding the sacks against the type-cylinder during their withdrawal by the hand, substantially as specified.

7. In a paper-sack holder and printer, the combination with a frame adapted to hold paper sacks in upright position, a type-cylinder, and an inking-roller, of segmental cams and gears, said cams adapted to move the inking-roller against the type-cylinder, and said gears adapted to rotate the type-cylinder, a pressure-roller carried by said cams, means on said cams for engaging with the segmental gears to lower them simultaneously with the downward movement of the pressure-roller and cams, and means for releasing the connection between the said cams and gears when the gears have reached the limit of the downward movement, substantially as specified.

8. In a paper-sack holder and printer, the combination with a type-cylinder, and inking devices for said cylinder, of segmental cams and gears adapted to elevate the inking devices and rotate the type-cylinder, means on said cams for permitting the inking devices to move away from the cylinder when the seg-

ment-gears have effected a rotation of said cylinder, a pressure-roller carried on said cams, and means for enabling the cams to engage with the segment-gears to move them after said cams have been actuated, substantially as specified.

9. In a paper-sack holder and printer, the combination with a holder in which the sacks are supportable in upright position, a type-cylinder, and an inking-roller, of segmental cams and gears for elevating said inking-roller and rotating said type-cylinder, means on said cams for engaging and moving downward therewith the said segmental gears, a cam for releasing said engagement between the segmental cams and gears when the said gears have reached the limit of their downward movement, and means for returning said segmental cams and gears to their upper or normal positions, substantially as specified.

10. In a paper-sack holder and printer, the combination with a holder, of a type-cylinder, gear-wheels on the shaft of said cylinder, an inking-roller, levers adapted to elevate said inking-roller, trip-pawls pivoted to said levers, segmental cams adapted to engage said trip-pawls to actuate said levers, segmental gears engaging with the gears on the type-cylinder to rotate said cylinder while the inking-roller is against it, and means for simultaneously actuating said cams and segmental gears, substantially as specified.

In testimony that we claim the foregoing as our own we hereto affix our signatures in presence of two witnesses.
